AUTOMATIC LUBRICATOR

Joseph Bijur, New York, N. Y., assignor to Auto Research Corporation, a corporation of Delaware

Application March 16, 1928, Serial No. 262,123

45 Claims. (Cl. 184—7)

My present invention relates primarily to centralized chassis lubrication, more especially of the automatic type.

It is among the objects of the invention to provide an installation of the type mentioned, involving a minimum of mechanism or linkage, and which may be operated by force derived from the vehicle in the normal use thereof, and which functions to propel the lubricant to the bearings at appropriate intervals under a propulsive force, to meet requirements, without excessive overflow and in particular dispensing with the need for mechanical reduction mechanism of any character.

Another object is to provide a construction of the above type which inherently, without the need for any special instrumentality for the purpose, will prevent the forcing of air under pressure from an empty reservoir into the pipe line, even though the pump have a tight-fitting piston.

A feature of the invention is the charging of the pump by forcing lubricant thereinto, while holding the outlet thereof closed, until the pump has been fully charged, at which time the valve is suddenly opened to permit discharge under a pressure, preferably stored during and by the pump charging operation.

The pump is preferably of the spring discharged type and includes a piston limited in its approach with respect to the valve to determine a sub-reservoir between the piston and the valve into which the lubricant is forced from the main reservoir.

In a preferred embodiment, the valve has a stem against which the piston is pressed by the spring in the intervals between charging operations, and toggle linkage connects the piston to the valve, to snap the latter open as soon as the piston has been displaced through its full stroke against the resistance of the discharge spring.

The charging operation may be effected by energy derived from the vehicle in the normal use thereof, as, for instance, from a pneumatic source, active in the normal operation of the vehicle, illustratively the intake or exhaust manifold or the brake air line.

In one embodiment, the pressure source such as that of the air brake line may be applied to an appropriate motor, illustratively on top of the lubricant reservoir, operating through a connecting link upon a servo-pump within the reservoir, which thus intermittently forces small charges of lubricant into the sub-reservoir. Alternatively the servo-pump may be operated from a suction motor conveniently located on top

of the reservoir and deriving its motive force from the intake manifold.

The servo-pump has a loose fitting piston, so that while effective to pump oil, it is ineffective to pump air. Accordingly, the main pump piston will not become displaced when the servo-pump operates in an empty reservoir, and since no air is forced into the main pump, the latter in discharge will at no times force air into the pipe line.

In another type of construction, pneumatic pressure, preferably from the brake air line is admitted into the lubricant reservoir, to place the lubricant therein under pressure and to force it slowly through a restriction member, such as a drip plug, into the sub-reservoir.

In the accompanying drawings in which are shown one or more of various possible embodiments of the several features of the invention,

Fig. 1 is a view in longitudinal section of a preferred form of tank and pump,

Fig. 2 is a diagrammatic view illustrating the mode of installation of the pump, showing a fragment of a preferred pipe system operated therefrom,

Fig. 3 is a diagrammatic plan view illustrating the mode of installation and use of the pump shown in Fig. 1,

Fig. 4 is a view similar to Fig. 1 of an alternative embodiment,

Fig. 5 is a view similar to Fig. 1 of another alternative form,

Fig. 6 is a bottom plan view of Fig. 5 with parts in section, and

Fig. 7 is a fragmentary view in longitudinal section of Fig. 5.

Referring now to Fig. 1 of the drawings, I have shown a lubricant reservoir R comprising a base section 10, within the flanged opening 11 of which there is fitted the lower enlarged end 12 of a pump cylinder 13. The top of the pump is turned inward as at 14 and retained firmly in position by an embossment 15 of the reservoir cover section 16, which is telescoped over the rim of the base section 10, and has a filling cap or plug (not shown). Vents 13a near the upper end of cylinder B prevent the building up of air or oil pressure above the pump piston.

A closure head 17 is pressed against the lower end of the pump unit by a threaded cap 18 screwed thereon, suitable gaskets 19 rendering the connection lubricant-tight. An outlet nipple member 20 is forced centrally through the head and is closed by a valve 21 to be hereinafter described.

Within the cylinder is a piston 22 comprising a block of metal to which a leather suction cup 23 is clamped by means of a nut 24 threaded upon the reduced end of the piston and pressed 5 against the washer. A stressed coil spring 25 is lodged in the upper part of the cylinder and reacts against the piston, preferably fitting at its lower end into a cavity 26 therein. The downward stroke of the piston is limited by screw 10 stops 39 extending inward from diametrically opposite sides of the cylinder 13, into longitudinal grooves 40 in the piston. The grooves 40 terminate at square shoulders 40' at their upper ends, which are arrested by stops 39 to limit the 15 descent of the piston.

The valve in the present embodiment has a head 21 within which is lodged a disk 27 of softer material, preferably vellumoid, to prevent the escape of lubricant from the reservoir or pump 20 during the intervals between operations. Preferably, the valve has a long stem 28 lodged at its upper end within a corresponding bore 29 in the piston structure. The volume of the cylinder between the piston and the valve, I 25 have designated a sub-reservoir, and designated by reference character S. This sub-reservoir is at all times filled with oil, which cushions the descent of the main pump piston and transmits pressure against valve 21 to aid in seating the latter. The oil in the sub-reservoir also maintains the piston cup 23 primed and impregnates the compressed soft disk 27 to render it effective as a seal.

Mechanical means is provided to release valve 30 21 after the charging stroke of the pump is completed and to reseat said valve when the discharge is completed. This valve actuating means acts with the oil pressure previously described, to press valve 21 against its seat throughout the 40 period between successive discharges. In a preferred construction this means comprises a toggle linkage intervening between the piston and the valve and located within the sub-reservoir. The linkage comprises a pivot 30 mounted in a bracket arm 31, rising from the head 17 and includes a toggle arm 32, pivoted by pin and slot connection 33 with respect to the valve stem 28 and an operating arm 34 connected by a link 35 to the piston 22. The link 35 is anchored at its 45 upper end by stud 36 to the piston 22 and has an elongated slot 37 at its opposite end for lost motion with respect to the link 34. A coil spring 38 connects the opposite ends of the toggle links. A stop 31a preferably integral with bracket 31 50 limits the upward stroke of toggle arm 32.

Bracket 31 is accurately located and maintained in position by pins 17a welded to the inside of cylinder 12 and passing through corresponding openings in the closure 11, which 60 mounts said bracket 31. The jamming or binding of the toggle linkage, which would easily be incurred by relative rotation of head 17 and piston 22 is avoided, the latter being held against rotation by the screw stops 39 previously described.

For charging the sub-reservoir, I have shown an auxiliary or servo-pump 41, supported by means of a fitting 42 at the wall of the sub-reservoir. The servo-pump has an outlet check valve 43 in the mounting fitting 42 normally seated by a coil spring 44, and an inlet check valve 45 in the lower end thereof, near the bottom of the reservoir 10 and seated by a coil spring 46. The servo-pump 41 comprises a small

cylinder within which moves a small piston comprising a metal rod 47 preferably devoid of packing. The servo-pump is preferably operated by motive means which may be mounted on top of the reservoir, to transmit its operating impulse 5 through a connecting rod 48 affixed at its upper end of the motive element by a small ball and socket joint 49 and connected by a similar joint 50 to the pump piston at its lower end.

The motor element is shown as operated by 10 pneumatic pressure. It comprises a cylinder 51 having a piston 52 with an appropriate leather cup 53 and normally retained in its upper position against head 51' by means of a coil compression spring 55 within the cylinder. 15

While the pump disclosed may be employed on distributing systems of various types, it is especially suitable with a system of the character disclosed and claimed in my prior Patent No. 1,632,771 of June 14, 1927. Illustratively, I have 20 shown in Fig. 2 a fragment p of a pipe line with a number of the drip plug outlets thereon. The specific construction of these, when taken alone, not being material to the present invention, it need merely be briefly noted that these drip plugs 25 each comprise preferably a fitting 65 with a metal pin 66 therein, affording a minute, highly 30 resistant flow-controlling crevice. A relief valve 67 is normally urged by a coil spring 68 against its seat to prevent slow drip through the fitting during the intervals between discharge. A felt 35 strainer plug 69 backed by a wire mesh screen 70 and lodged in a corresponding socket at the inlet to the fitting, excludes solid particles and thereby guards the pin crevice from being clogged 40 and the relief valve from leaking. At T is shown the exterior of one of the drip plugs in the run of the pipe line and embodied in a T fitting.

Illustratively the tank R is shown affixed to the dashboard D at the engine side thereof, and the head of the distributing piping is connected to the outlet 20.

For operating the motor 51, I may employ the engine exhaust or other source of pressure, but I have illustratively shown the air brake 45 line 56 on the vehicle through which compressed air flows to the brakes from a tank 57 when the brake pedal 58 is depressed. The air tank is charged from air compressor 59, driven from the engine 60. A pressure governor 61 operatively connects the compressor to the engine when the air pressure in the tank is low. A check valve 62 in the tank prevents return flow of compressed air. A pipe line 63 communicates from air brake line 56 to the nipple 64 in the 55 head of cylinder 51.

Whenever the air brakes are applied, pressure is communicated through pipe 63 and nipple 64, to depress the piston 52 against the resistance of spring 55. By the thrust thus transmitted 60 through connecting rod 48, the piston 47 of the servo-pump is depressed, thereby to force a small charge of oil past the check valve 43 into the sub-reservoir S, and forcing the piston 22 slightly upward against the resistance of spring 25. 65 When the pressure on pedal 58 is released and pneumatic pressure on line 56 ceases, the coil spring 55 again lifts the piston 52 and through the connecting rod 48 raises the piston 47 of the servo-pump and thereby causes the latter 70 to draw in a fresh charge of lubricant from the reservoir, past the check valve 45 preparatory to discharge into the sub-reservoir when the air brake is again applied. Thus, for each discharge 75 of the servo-pump, the piston 22 of the main

5 pump is forced upward slightly. During this operation, the coil spring 38 of the toggle maintains the valve 21 pressed against its seat. This 10 operation proceeds until the pump has been charged, at which time the link 35 has been moved with the piston to thereby draw the toggle link 34 past dead center. The tensioned toggle spring 38 immediately thereafter contracts to 15 suddenly lift the valve stem 28 and thereby sharply open the valve 21 and allow the pump to discharge through the outlet 20, under the expansive force of coil spring 25.

10 The oil pressure in the sub-reservoir presses the outlet valve 21 closed while the trip mechanism is changing from the position of "push down" to that of "lift up". Thus during the charging operation, the outlet cannot open, so that the rise of the main piston is assured, until snapping of the toggle mechanism has occurred.

20 The various drip plugs in parallel present a relatively high resistance to discharge, so that the drip plugs at the outlets will substantially retard the rapid discharge of the pump which would otherwise occur under the substantial expansive force of the spring 25, suddenly released by the quick opening of valve 21, as above described. Thus, whenever the pump has been completely charged, the discharge to the bearings will occur under the nearly constant force determined by the compression spring 25, the rate of discharge being determined by the constant characteristics of the various drip plugs at the bearings.

25 The charging of the pump occurs without any conscious effort or attention whatsoever on the part of the operator and at the relatively long time elapsed before a multiplicity of brake operations have occurred. The discharge or lubricating action will, therefore, occur only once for several miles of vehicle operation, and the pump volume is so proportioned that at each discharge, there will be sufficient lubricant delivered to the bearings to supply the needs thereof for the intervals between successive pump operations.

30 Obviously, air as distinguished from oil will not be pumped by the servo-pump, but will leak past the piston thereof. It follows that the main pump will never be charged with air, though operated with the main reservoir depleted, and no air can be forced into the distributing oil line. The reliability of distribution will thus not be impaired, as it would be by forcing air thereinto.

35 It will be readily seen that in the initial use of the new tank the air in the sub-reservoir will readily escape past the suction cup 23 until the oil has risen and the trapping of air is thus avoided.

40 In Fig. 4 I have shown a reservoir and pump construction identical with that of Fig. 1, in which the pressure motor is replaced by a suction motor 75 operated preferably from the intake manifold (not shown). The suction motor is connected by means of the connecting rod 76 to the piston 77 of the servo-pump 78 in the same manner as is the pressure motor in Fig. 1.

45 The suction motor may be of identically the same construction as that shown in my copending application, Serial No. 580,668 filed August 9, 1922. I will but briefly describe it here as comprising a cylinder 75 having a piston 79 therein urged by a coil spring 83 toward the lower end of the stroke, the coil spring reacting against the cylinder head 81. The venting of

5 the cylinder at the end of the suction stroke occurs through a vent tube 82. The suction and venting ports are respectively controlled by corresponding valves 84 and 85 coacting with a toggle spring 86 which, in turn, is operated by pins 87 and 88 at opposite sides thereof mounted on a rod 89 secured axially of the piston 79.

10 In operation, upon application of suction, past open valve 84 the piston 79 is drawn upward until the pin 88 snaps over the toggle 86 at 15 which time the suction valve 84 is raised to its seat and the venting valve 85 is raised from its seat. In the subsequent spring-return of the piston 75 during which the servo-pump 78 is operated, the pin 87 returns the toggle spring to 15 re-open the suction valve 84 and reclose the venting valve 85 preparatory to the next suction stroke.

20 Thus, while the engine is operating, the servo-pump is slowly reciprocated until after the main pump is fully charged, lubrication occurs, as set forth above. The operation is at time intervals, depending roughly on manifold vacuum determined by vehicle operating conditions.

25 At 90 is shown the vacuum shut-off valve drawn upward against the resistance of spring 91 to its seat 92, to prevent operation of the suction motor during the application of the high suction occurring when the engine is idling. The valve has a unitary piston 90' which is raised under high 30 suction to close valve 90. Piston 90' is perforated at 91' to transmit the suction impulse which operates motor 75.

35 In Figs. 5, 6 and 7 is shown a pressure operated embodiment in which the servo-pump is dispensed with. The propulsive agency for operating the main pump may be pneumatic pressure derived from the air line, as in Fig. 2, but applied directly to the interior of the oil reservoir R. The lubricant in the main reservoir R is thereby placed under compression and lubricant slowly forced into the sub-reservoir S' through a highly restricted passage in the wall of the latter, near the bottom of the main reservoir. The restriction passage may be substantially a drip plug construction similar to that shown in Fig. 1 but devoid of a valve. Illustratively the restriction plug comprises a fitting 100 threaded into the wall of the sub-reservoir, having its longitudinal bore nearly filled by a metal pin 101 extending substantially the length thereof and maintained from dropping or working out of the bore by wire mesh caps 102 in corresponding end sockets 103, and in turn maintained in position by perforated sheet metal cups 104 forced into the extremities of said 45 sockets.

50 There being no motor element on top of the reservoir, I have in this embodiment illustratively shown a longer pump cylinder 105, to fit tightly in a flanged opening 106 in the top of the reservoir above which it protrudes. The lower part of the pump construction is substantially identical with those of Figs. 1 and 4.

55 The compressed air is preferably admitted to the reservoir through a special fitting having a stud 107 mounted in the top of the tank. The fitting includes an integral capsule 108 extending preferably laterally of the reservoir within which capsule is fitted a removable filter disk 109 having 60 a wire mesh backing screen 110 and clamped peripherally by means of a ridge 111 on plate 112 which in turn is held in position by a closure cap 113 threaded upon the capsule. The cap includes a nipple 114 upon which the pipe 115 75

from the air tank is secured by means of an appropriate coupling 116.

The nipple communicates with an aperture 117 through the pressure plate 112, thence through 5 the filter 109 and 110 and bore 118, thence by way of a bore 119 longitudinally of the mounting stud 107 into the reservoir. A disk valve 120 controlling admission of air to bore 119 will be described below.

10 Preferably there is provided in addition to the filter 109 for cleansing the compressed air, a removable filter 121 similar to filter 109 but for intercepting any particles from the oil prior to its passage to the restriction plug 100. Filter 15 121 is lodged within closure cap 122 and is maintained compressed at its periphery by the ridge 124 on a pressure disk 123 which is in turn held at its periphery against the lower edge of a short cylinder 125 fitted into a corresponding flanged opening 126 in the bottom of the reservoir and locked thereat by a split ring 127. Communication with the restriction plug 100 in the wall of the sub-reservoir S'' is effected through a short pipe 128 held at one end by 20 a coupling 129 at the outlet nipple 130 of cap 122, and similarly secured at its opposite end by means of coupling 131 to restriction plug 100.

In the absence of special precautions, should 30 the reservoir R'' become depleted of oil, the continued application of air pressure might result in forcing the oil out of the pipe lines, thereby impairing the subsequent operation of a system such as that indicated in Fig. 2.

I have provided float controlled means to 35 control disk valve 120 in order to prevent the application of high air pressure to the reservoir when the latter is empty. Disk valve 120 has a soft seating ring 132 above an angular seating ridge 133 in the stud 107.

40 The valve has a stem which extends above the valve disk as at 134 as well as therebelow as at 135. The upper part of the stem is guided in a corresponding hub 136 within a closure plug 137 threaded into the hollow upper end of stud 107, while the lower part of the stem 135 extends axially through the stud 107.

Secured to the lower end of the stem 135 is a 45 light rod 138 to the lower extremity of which float F is secured. When the tank has oil therein the float is elevated and the valve 120 is above its seat so that compressed air can enter the reservoir in the manner previously described. When however the reservoir becomes nearly empty the float drops sufficiently to seat the valve 120. Accordingly if at such time air pressure be applied at 50 pipe 115, such pressure would only be effective as is obvious, to force the valve 120 more tightly against its seat 133 but could not be transmitted to the interior of the reservoir.

60 I have moreover provided means to discharge applied air pressure to relieve the reservoir when it becomes drained, of any residual air pressure therein. For this purpose the valve stem 134-5 is preferably provided with a longitudinal bore 65 140 through the length thereof. The lower part of bore 140 has a communicating cross bore 141 opening into the reservoir. Near the upper end, the stem has another cross bore 142 which registers, when the valve 120 is seated, with a pair 70 of downwardly inclined bores 143 in the hub 136 of plug 137. Hub 136 which is closed at its upper end except for a vent opening 136' is preferably provided with a flange 144 immediately above the bores 143, serving to shield the latter from 75 clogging.

When there is oil in the reservoir and the valve 120 is raised above its seat, the cross bore 142 enters the upper part of the hub 136 out of communication with bores 143. The continued application of compressed air serves only to force the valve 120 upward against the hub 136 to close said bores, so that the compressed air through pipe 115 has no path of escape and will be forced into the reservoir. 5

The upper part of the pump cylinder 105 is 10 preferably vented at 146 to avoid the resistance due to the compression of air therein. In order to prevent the entry of dirt through these ports I provide a cup 147 loosely fitted over the upper part of the pump cylinder and held in place 15 thereon by a central bolt and nut 148.

To afford a ready path of escape for any lubricant that may leak above the piston 22'', I preferably provide a short drain pipe 149 through the wall of the pump cylinder at the upper part 20 thereof, opening downward preferably along the reservoir wall as shown, to freely drain any such leakage, to an inconspicuous place.

If desired a whistle or other pneumatic sounding device (not shown) may be associated with 25 the port 134 so that there will be an audible sound when air pressure is relieved thereat, thereby to apprise the user of the need for refilling.

I claim:—

1. A pump, a discharging agency therefor, an 30 outlet valve, means to energize the pump discharge agency and linkage automatically operated from the pump, when it contains a definite charge to open the valve, in order to release the pump discharge agency. 35

2. The combination of a lubricant supply installation comprising a lubricant reservoir, and a pump having an ejector, a valve at the outlet of said pump, means to gradually inject lubricant between said valve and said ejector and thereby 40 to charge said pump, and means correlated with said elements to positively open said valve when the pump is completely charged.

3. The combination of a lubricant container, a pump cylinder associated therewith, a spring 45 discharged piston in said cylinder, a valve at the outlet of said cylinder, means normally retaining said valve in closed position, means to force lubricant under pressure into the chamber between the piston and the valve, to urge the piston in direction opposed to the stress of said spring, and means controlled from said piston to thereupon open said valve, to permit discharge of said pump.

4. A lubricant supply installation comprising 55 a reservoir, a pump cylinder extending longitudinally thereof, a piston in said cylinder, a coil spring urging said piston in one direction, said cylinder having a sub-reservoir beyond said piston, at all times filled with lubricant, a valve 60 at the outlet of said sub-reservoir, means normally retaining said valve closed, an inlet from said reservoir to said sub-reservoir, means for forcing lubricant through said inlet and thereby urging the piston against the resistance of said 65 spring, and means effective after a predetermined period of operation, to release the valve closing means in order to permit discharge of the pump.

5. A lubricant supply installation comprising 70 a reservoir, a pump cylinder extending longitudinally thereof, a piston in said cylinder, a coil spring urging said piston in one direction, said cylinder having a sub-reservoir beyond said piston, at all times filled with lubricant, a valve 75 at the outlet of said sub-reservoir, means normal-

- ly retaining said valve closed, an inlet from said reservoir to said sub-reservoir, means for forcing lubricant through said inlet and thereby urging the piston against the resistance of said spring, 5 means effective upon a predetermined stroke of said piston to release the valve closing means in order to permit discharge of the pump, and means controlled from said piston at the end of its discharge stroke, to reclose said valve.
10. A lubricant pump comprising a cylinder, a piston therein, a spring urging the said piston toward the discharge end of the cylinder, a valve closing the outlet from said cylinder and normally urged to closing position, means for admitting lubricant under pressure between said piston and said valve, a lost motion connection between said piston and said valve whereby to maintain the latter closed during the charging action of the piston and to open said valve when the charging is completed, to thereupon permit automatic discharge of the pump.
15. A pump structure including a cylinder, a piston therein, a valve at the pump outlet normally seated to prevent pump discharge, a toggle urging said valve toward its seat, means connecting said toggle to the piston, means to pump lubricant under pressure into the chamber between said piston and said valve, whereby upon admission of a predetermined charge of lubricant into said chamber, the toggle will be snapped to open said valve in order to permit discharge of lubricant.
20. A lubricant pump comprising a cylinder, a piston therein, a spring urging said piston toward the discharge end of the cylinder, a valve closing the outlet from said cylinder, means for admitting lubricant under pressure between said piston and said valve, thereby to hold the valve in closed position and to cause the piston to recede from the valve, and means to cause the valve to open at a rate of movement faster than the progress of the piston, as the latter reaches the end of its charging stroke.
25. A pump structure including a cylinder, a piston therein, a valve at the pump outlet normally seated to prevent pump discharge, a toggle normally urging said valve towards its seat, means connecting said toggle to the piston, means to pump lubricant under pressure into the chamber between said piston and said valve, whereby upon admission of a predetermined charge of lubricant into said chamber the toggle will be snapped to open said valve in order to permit discharge of lubricant, and means transmitting a direct thrust from the piston to return the valve to seated position at the end of pump discharge.
30. A lubricant pump comprising a cylinder, a valve closing the outlet of said cylinder, a piston in said cylinder, a spring urging said piston toward said valve, a lubricant chamber being formed between said piston and said valve, a toggle to normally urge said valve to closed position, means for admitting lubricant laterally into the chamber between said piston and said valve, said toggle being connected to said piston to be operated therefrom for snapping the valve to open position at the end of the pump charging stroke.
35. A lubricant pump comprising a cylinder, a piston therein, a lubricant chamber beyond said piston a valve closing the outlet from said chamber, a spring stressed to move said piston toward said valve, said valve being normally maintained closed, means to inject lubricant under pressure into said chamber, thereby to dis-
- place said piston against the resistance of said spring, and means to automatically draw said valve away from its seat after the piston has been displaced to a predetermined extent, to thereupon permit spring discharge of the pump.
40. In a lubricant pump, a cylinder, a piston therein, a valve normally closing the outlet of said pump, spring toggle means to open the valve at the end of the pump charging stroke, said toggle means comprising a fixed mount, and a pair of spring-connected arms, one of said arms being connected to the valve and the other to the piston.
45. In a chassis lubricating installation, a self-discharging lubricant pump having a charging chamber, a valve normally closing the outlet therefrom, means operated by power derived in the normal operation of the vehicle for intermittently forcing small charges of lubricant into the chamber to charge the same, and means to automatically open said valve when a predetermined charge has been admitted.
50. In a chassis lubricating system, the combination of a reservoir, an upright pump cylinder having an outlet at the bottom thereof, a valve normally closing said outlet, a spring in back of said piston to normally urge the latter towards said valve, means limiting the stroke of said piston to determine an oil-filled chamber between said piston and said valve, means operated intermittently by power derived in the normal operation of the vehicle to slowly force lubricant from said reservoir into said pump chambers to force the piston upward against the resistance of the spring, and means interlocked with said piston to suddenly open said valve, when the piston has reached a predetermined position, whereby the pump will thereupon be discharged by the expansive force of said spring.
55. In a chassis lubricating system, the combination of a lubricant reservoir, a self-discharging pump associated therewith including a piston and an outlet valve, means for admitting successive charges of lubricant under pressure between said valve and said piston to displace the latter, means to automatically open said valve after a predetermined number of charges, said intermittent charging means being operated by power derived in the normal operation of the vehicle.
60. The method of chassis lubrication, employing a distributing system having highly restricted flow proportioning outlets, which consists in applying power derived from the normal operation of the vehicle, to force lubricant into the inlet of a chamber and simultaneously closing the outlet and simultaneously causing said lubricant upon being forced into said chamber to store energy, and closing the inlet and opening the outlet of the chamber to relieve the stored energy for discharge from the chamber toward the bearings to be lubricated after lubricant is forced into said chamber and energy has been stored therein, said chamber receiving the total charge of lubricant to be supplied to the chassis bearings when lubricant is forced thereinto and discharging said total charge toward said bearings under sufficient pressure to assure proper distribution by said proportioning outlets.
65. In a chassis lubricating system, the combination of a reservoir, a sub-reservoir supplied therfrom, means resiliently resisting change in volume of said sub-reservoir, means automatically operated by power derived in the normal operation of the vehicle for intermittently forcing lubricant from said reservoir into said sub-

reservoir, and means for opening said sub-reservoir after it has been expanded to a predetermined volume to permit the resiliently stored energy to discharge lubricant therefrom.

5 18. In a chassis lubricating system, the combination of a reservoir, a sub-reservoir supplied therefrom, means resiliently resisting change in volume of said sub-reservoir, a valve opening inward into said sub-reservoir, means automatically operated by power derived in the normal operation of the vehicle for intermittently forcing lubricant from said reservoir into said sub-reservoir, to urge said valve against its seat and to cause expansion in the volume of the sub-10 reservoir, and positive means for opening said valve inwardly after the sub-reservoir has been expanded to a predetermined volume, to permit the resiliently stored energy to discharge lubricant.

15 19. In a chassis lubricating system a lubricant reservoir, a sub-reservoir in communication therewith and leading to the piping system, a valve normally closing said sub-reservoir, a piston resiliently urged toward said valve, means for intermittently operating said small pump by power derived from the vehicle, thereby limiting the approach of said piston with respect to said valve, a small pump for forcing lubricant from said reservoir into said sub-reservoir, means for intermittently operating said small pump by power derived from the vehicle, thereby 20 to store energy in back of said piston, and a mechanical connection between said piston and said valve to automatically open the latter after a predetermined number of strokes of said small pump.

25 20. In a chassis lubricating system, the combination of a reservoir, a sub-reservoir in communication therewith, a valve normally closing the outlet from said sub-reservoir, a spring-urged piston interlinked with said valve to open the latter upon predetermined displacement of the former, a small pressure pump adjacent to said sub-reservoir for forcing lubricant thereinto from said reservoir, a source of pneumatic power on the vehicle and means for intermittently operating said small pump from said source of power.

30 21. In a chassis lubricating system, the combination of a lubricant reservoir, a pump member therein having a valve at the outlet thereof, a piston, means limiting the approach of said piston to said valve to determine a sub-reservoir therebetween, resilient means resisting the admission of lubricant into said sub-reservoir, a small pump in said reservoir for forcing lubricant therefrom into said sub-reservoir, motive means for said pump on top of said reservoir, linkage connecting said motive means to said pump, a source of energy upon said vehicle for intermittently operating said motive means and means to open said valve when a predetermined quantity of lubricant has been admitted to said sub-reservoir.

35 22. In a chassis lubricating system, the combination of a lubricant reservoir, a pump member therein having a valve at the outlet thereof, a piston, means limiting the approach of said piston to said valve to determine a sub-reservoir therebetween, resilient means resisting the admission of lubricant into said sub-reservoir, a small pump in said reservoir, for forcing lubricant therefrom into said sub-reservoir, a pneumatically operating motive means disposed on top of said reservoir, a rod extending into said reservoir and connecting said motive means to said pump, a source of pneumatic pressure upon

said vehicle for intermittently operating said motive means and means to open said valve when a predetermined quantity of lubricant has been admitted to said sub-reservoir.

40 23. A chassis lubricating supply installation comprising a reservoir, a pump unit comprising a cylinder extending longitudinally through said reservoir, and protruding therebelow, a valve seated at the outlet from said pump and having an upstanding stem, a piston, a spring above said piston reacting against the top of said pump unit to force said piston toward said valve stem, a servo-pump within said reservoir laterally of said pump for forcing lubricant thereinto from said reservoir, a pneumatic motor on top of said reservoir having a linkage connection to said servo-pump for operating the latter, means for intermittently operating said pneumatic motor to actuate said servo-pump and force lubricant into said cylinder, and linkage interconnecting 45 said piston and said valve to automatically open the latter upon admission of a predetermined charge of lubricant into said pump.

24. In a chassis lubricating system, a spring discharged lubricant pump, a servo-pump for 25 charging the latter, a valve preventing discharge from said pump during the charging operation, means for automatically opening said valve to permit discharge of said pump at the end of the charging stroke, said vehicle having a source of 30 pneumatic pressure intermittently applied in the normal operation thereof, and means for operating said servo-pump through one stroke for each application of pneumatic pressure.

35 25. In a chassis lubricating system, a spring discharged main lubricant pump, a servo-pump for charging the same, a valve preventing discharge from said main pump during the charging operation, means for automatically opening said valve to permit discharge of said pump at 40 the end of the charging stroke, a pressure motor comprising a cylinder, a spring returned piston therein, a link connecting said piston to said servo-pump, a brake air line and means applying pressure therefrom to said pneumatic motor. 45

26. In a chassis lubricating system, a spring discharged lubricant pump, a servo-pump for charging the same, a valve preventing discharge from said main pump during the charging operation, means for automatically opening said 50 valve to permit discharge of said pump at the end of the charging stroke, a suction motor on top of the reservoir, a link connecting said motor to said servo-pump, said motor having automatic control means for determining reciprocation 55 thereof under a continuous suction force applied thereto, and a pipe connecting said suction motor to apply suction thereto from the intake manifold of the engine.

60 27. The combination of a reservoir, a pump, a piston therein, a spring for discharging said pump, a valve normally closing the outlet from said pump, means for slowly admitting lubricant from said reservoir into the chamber between said piston and said valve to displace said piston 65 against the resistance of the discharge spring, means to automatically open said valve upon completion of the pump charge to permit automatic discharge therefrom, said pump charging means comprising an inlet, a source of pneumatic pressure delivering therethrough into the reservoir and a highly restricted duct in the wall of said sub-reservoir, through which lubricant is slowly forced thereinto under the pneumatic pressure in said reservoir. 70

28. In a chassis lubricating system, the combination of a lubricant reservoir, a pump unit therein, having a valve normally closing the outlet thereof, a pump piston, a spring normally urging said piston toward said valve, means limiting the approach of said piston with respect to said valve to determine a sub-reservoir therebetween, a pneumatic brake tank on the vehicle, a compressor for charging said tank, a brake air line connecting said compressor to said tank, a pipe line connecting said brake air line to said reservoir, and a highly restricted inlet plug at the wall of said sub-reservoir to retard the admission of lubricant thereto under the pneumatic pressure applied to said reservoir, thereby to slowly retract said pump piston against the resistance of said spring, and means for automatically withdrawing the valve from its seat at the end of the pump stroke to permit spring discharge of the pump.
29. In a chassis lubricating system of the type having instrumentalities for determining the division of lubricant and for maintaining the distributing piping substantially filled with oil at all times; the combination therewith of a self-discharging pump having a tight-fitting ejector for injecting lubricant into the head of the system, means for forcing lubricant under pressure into the pump, to cause said ejector to recede, said pressure means being selective to exert pressure upon lubricant, but to allow air to escape thereby.
30. In a chassis lubricating system a lubricant containing vessel, a source of lubricant propelling energy, means for intermittently applying pressure from said source to the contents of the vessel, and means to automatically prevent communication between the source and the vessel and to relieve the pressure in said vessel when less than a predetermined quantity of lubricant remains in the vessel.
31. In a chassis lubricating system, the combination of a lubricant reservoir, means for applying pneumatic pressure thereto, including a fitting at the top of said reservoir, said fitting including a capsule having a filter therein through which the pneumatic agency is passed, and a lubricant controlled valve in said fitting arranged to close automatically when insufficient lubricant remains in the reservoir, thereby to prevent the admission of pneumatic pressure into the reservoir.
32. A lubricating system including a lubricant reservoir, a source of pneumatic pressure, means connecting said source to said reservoir for intermittently applying pneumatic pressure to the lubricant within the reservoir, a pump within the reservoir, means for effecting communication between the reservoir and the pump, for slow charge of the latter under the pneumatic pressure, means to automatically release the pump and permit discharge thereof after completion of the charge, and valve means to automatically vent the reservoir when the level of lubricant therein is decreased to a predetermined level.
33. In a chassis lubricating installation, a distributing piping system having flow controlling outlets, a container at the head of said piping system, a valve controlled inlet and outlet respectively to and from said container, said outlet being closed when said inlet is open and said inlet being closed when said outlet is open, means for forcing lubricant under pressure through said valve controlled inlet and resilient means in said container stressed by the lubricant forced through said inlet for applying pressure to the lubricant in said container to force lubricant therefrom through said outlet into said piping system, said inlet being open and said outlet being closed when lubricant is forced into the container and said outlet being open and said inlet being closed when said lubricant is forced into said piping system.
34. A lubricating system, comprising a vessel containing lubricant, a source of pneumatic pressure, means for intermittently establishing communication from the source to the vessel, valve means to shut off the application of pneumatic pressure to the reservoir and means automatically actuating said valve means when the charge of lubricant remaining in the reservoir is little.
35. In a lubricating system, the combination of a lubricant reservoir having an outlet adapted to communicate with a distributing piping system, a source of pneumatic pressure, piping establishing communication between said source and said reservoir, a float in said reservoir, a valve under the influence of said float, and adjacent the pneumatic inlet to said reservoir, whereby when the float drops, the valve will seal communication under the influence of pressure on said reservoir.
36. In a lubricating system, the combination of a reservoir, a self-discharging pump associated therewith, means for forcing lubricant from said reservoir into the charging chamber of said pump, said means comprising a source of pneumatic pressure in communication with said reservoir, a passageway from said reservoir into said charging chamber, presenting high resistance to oil flow, and a filter substantially at the inlet of said passageway.
37. A lubricant reservoir, a pump extending therethrough and secured therein, a filling opening in the top of said reservoir, a replaceable filter structure secured in the bottom of said reservoir, laterally of said pump, and a pipe connection from the filter structure to the pump.
38. A lubricating system including a reservoir having a fitting in the top, said fitting having a valve therein, a float in said reservoir controlling said valve, a fluid feed line to said reservoir controlled by said valve and serving to create a pressure in said reservoir substantially departing from atmospheric, means to cause said valve to close said line when the lubricant is almost depleted in said reservoir, venting means to vent said reservoir to the atmosphere and means to actuate said venting means to vent said reservoir when said valve is closed.
39. A lubricant reservoir comprising the combination of a vessel, a pump cylinder extending vertically of said vessel, the upper end of the cylinder projecting above the top of said vessel and frictionally secured therein, a piston in said cylinder, a spring above said piston reacting against the top of said cylinder to urge the piston downward, ports in the top of said cylinder to vent the latter, a guard cup of larger diameter telescoped over and spaced from the vented end of said cylinder and secured thereto, and a drain pipe through said pump to permit escape of any lubricant that has passed above the pump piston.
40. In a chassis lubricating system of the type comprising piping having pressure-actuated outlets for determining the division of lubricant therefrom and for maintaining said piping substantially filled with lubricant at all times; the combination therewith of a pump cylinder, a tight-fitting piston therein, a spring for discharging the pump, a valve at the head of the piping and normally closed, and a servo-pump for forcing oil into the space between the valve and the

piston to cause the latter to recede, said servo-pump being selective to by-pass air, and means to open the valve and allow discharge of the pump into the pipe system after the pump has been completely charged.

41. The method of chassis lubrication, employing a distributing system having highly restricted flow proportioning outlets, which consists in applying power derived from the normal operation 10 of the vehicle, to force lubricant into a chamber, said chamber being provided with a resilient agency occupying a considerable portion of the volume within said chamber, which volume is decreased when lubricant is forced into said chamber, said resilient agency storing energy upon such decrease in volume, and after the chamber has received a charge of lubricant and said resilient agency has stored energy, then opening the chamber to relieve the stored energy for automatic discharge 15 from the chamber toward, and for automatic distribution to, the bearings to be lubricated, said chamber receiving the total charge of lubricant to be supplied to the chassis bearings when lubricant is forced thereinto and discharging 20 said total charge toward said bearings under sufficient pressure to assure proper distribution by said proportioning outlets.

42. In a lubricating device for bearings, a plurality of outlet devices; discharge control means 30 in each device, a conduit connecting said devices, a measuring chamber having an outlet connected to said conduit and an inlet, means for forcing lubricant in small charges into said inlet under pressure over a long period of time, a valve controlling said outlet, and lubricant pressure operated means for operating said valve when a predetermined quantity of lubricant has been forced 35 into said chamber to discharge said lubricant in a short period of time.

40 43. A central lubricating system comprising a resiliently cushioning receiving chamber having associated therewith an inlet port and an outlet port, a valve device controlling said outlet port,

mechanically operated pump means for delivering lubricant under pressure through said inlet port, branched conduit means leading from said outlet port to deliver lubricant to points requiring lubrication, lubricant pressure-responsive metering means determining the emission to said respective points, means for shifting said valve device to closed position, and automatic means to propel the valve device of the lubricant charged chamber to wide open position, thereby to permit 10 resilient propulsion of lubricant therefrom into the branched conduit means.

44. In a lubricating system for a mechanism having a plurality of bearings to be lubricated, distributing piping with inlet means and a plurality of outlets to said bearings, and pressure means to force lubricant under pressure into the inlet means, said pressure means including a source of pneumatic pressure, a reservoir containing lubricant, means to apply said pneumatic 20 pressure to the lubricant body in said reservoir, accumulator means, conduit means to convey lubricant from said reservoir to said accumulator means, means to discharge said accumulator means into said inlet means and restriction means 25 to limit the lubricant flow through said conduit means from said reservoir to said accumulator means.

45. In a lubricating system for a mechanism having a plurality of bearings to be lubricated, distributing piping with inlet means and a plurality of outlets to said bearings, and pressure means to force lubricant under pressure into the inlet means, said pressure means including a source of pneumatic pressure, a reservoir containing 30 lubricant, means to apply said pneumatic pressure to the lubricant body in said reservoir, means to cut off said source from said reservoir when less than a predetermined quantity of lubricant remains in the reservoir and means to relieve the pneumatic pressure in said reservoir when so cut off.

JOSEPH BIJUR.
